COMB CLEANER

Hing Seto, Los Angeles, Calif.

Application May 14, 1940, Serial No. 335,053

1 Claim. (Cl. 132—28)

The object of the invention is to provide a comb cleaner of simple construction which may be readily attached to a comb of usual construction for removing any foreign matter that may 5 collect between the comb teeth.

Other objects and advantages will be apparent from the following description reference being had to the accompanying drawing in which:

Fig. 1 is a side elevation of a comb provided 10 with the cleaner.

Fig. 2 is a section taken on line 2—2 of Fig. 1.

Fig. 3 is a top plan view.

Fig. 4 is a bottom plan view.

Fig. 5 is a perspective view of the comb cleaner.

Fig. 6 is a detail section taken on line 6—6 of 15 Fig. 1.

Fig. 7 is a section taken through a comb provided to receive the comb cleaner of this invention.

Fig. 8 is a detail section taken through the 20 cleaner.

Referring more specifically to the drawing 10 designates a comb of usual form comprising a body portion 11 having teeth 12 thereon, the body having a flat side that is engaged by the cleaner 25 13.

The cleaner 13 preferably consists of an elongated metal plate 14 or other rigid material having a plurality of prongs 15 disposed at right angles thereto that extend between the teeth 12 when mounted on the comb as clearly shown in Figs. 2 and 4.

The side edges of the plate are beveled at 16 and engage corresponding faces 17 formed on 30 35 lugs or projecting portions 18 formed on one side

of the comb body, and secured to the plate 11 is a knob or projection 20 whereby the cleaner may be moved to clean the comb.

Thus it will be seen that the cleaner is held in place on the comb body by a dove-tail connection 5 which provides sufficient friction to prevent it from accidentally becoming disengaged therefrom, yet will permit it to slide freely on the body.

It will also be noted that as the prongs of the 10 comb cleaner are disposed between the comb teeth, at their upper ends, when in place on a comb, it will be apparent that any foreign matter that accumulates between the comb teeth will be instantly removed therefrom when the 15 cleaner is moved downwardly or removed entirely from the comb.

From the foregoing it will be seen that the cleaner does not in any way interfere with the use of the comb, yet provides easy and convenient means for cleaning it. 20

I claim:

A comb cleaning device comprising a comb of usual construction having at each end a vertical dove-tail groove, said grooves being oppositely 25 disposed, and a comb cleaning member slidably engaging the grooves of said comb and consisting of a substantially flat metal plate provided on its lower horizontal edge with a plurality of prongs adapted to project between the comb 30 teeth, the vertical ends of said member being bevelled to engage the dove-tail grooves of the comb and frictionally hold the cleaning member in engagement therewith.

HING SETO. 35
